UNITED STATES PATENT OFFICE

98,992

DESIGN FOR A KNITTED FABRIC

William J. Beniston, Seaford, N. Y., assignor to Julius Kayser & Co., New York, N. Y., a corporation of New York

Application January 30, 1936, Serial No. 60,887

Term of patent 3½ years

To all whom it may concern:

Be it known that I, William J. Beniston, a citizen of the United States, residing at Seaford, Nassau County, State of New York, have invented a new, original, and ornamental Design for Knitted Fabric, of which the following is a specification, reference being had to the accompanying drawing, forming part thereof.

The single figure of the drawing is a plan view of a piece of knitted fabric showing my new design. The face of the fabric is shown at the right and the back of the fabric is shown at the left.

I claim:

The ornamental design for a knitted fabric, as shown.

WILLIAM J. BENISTON.
